UNITED STATES PATENT OFFICE.

ALBERT L. HAMAN, OF ST. PAUL, MINNESOTA.

WATCHCASE.

Application filed August 11, 1919. Serial No. 316,613.

To all whom it may concern:

Be it known that I, ALBERT L. HAMAN, a citizen of the United States, residing at St. Paul, in the county of Ramsey and State of Minnesota, have invented certain new and useful Improvements in Watchcases, of which the following is a specification.

This invention relates to swing-ring watch cases and more particularly to improvements in anti-magnetic attachments designed to be applied to the swinging ring of the watch case.

An object of the invention is to provide a dividing wall in the interior of the watch case located between the back of the watch case and the swing-ring, said wall being made preferably of soft iron to absorb magnetism, and being bodily instantly removable from the watch case.

20 A further object of the invention is to provide anti-magnetic means in a watch case of the class described which may also serve as a protecting shield for the movement mounted in the ring.

25 A still further object of the invention is to provide anti-magnetic means in watch cases of the class described which may be applied as an attachment to standard makes.

The invention consists in the construction, 30 combination and arrangement of parts hereinafter described and claimed. In the accompanying drawings forming part of the specification

Fig. 1 is a vertical sectional view through 35 the center of a watch case and its pendant embodying the invention.

Fig. 2 is a plan view of a watch case embodying the invention, the cover of the case not being shown.

40 Fig. 3 is a perspective view of the shield or cap removed from the watch case, and

Fig. 4 is a fragmentary perspective view of a section of the swing-ring.

Referring to the drawings, A represents 45 the body portion of a circular watch case formed elliptical in cross section and provided with a radially disposed cylindrical pendant B, its longitudinal axis coinciding with the major axis of said ellipse, the pendant 50 extending outwardly from the periphery of the body portion.

Offset in a direction away from the back 1 of the body portion from said major axis is the annular inwardly extending flange 2 integral with the upper edge of the body portion 55 of the watch case. The flange 2 surrounds a

center aperture 3 surrounded by an integral upwardly extending ring portion 4, whereby is formed a recess 5 around said aperture. Screw threaded on the flange portion 4 is a 60 cover 6 formed with a bezel 7 adapted to hold a crystal 8.

Hinged on one side of the flange 4 by means of pivot 9 is the swing-ring C. The swing-ring is formed with a shoulder 10 65 adapted to seat in the recess 5, the ring being formed so as to be flush with the top of the flange portion 4 when in seated position.

The ring as shown is comparatively deep and is adapted to receive a watch movement 70 not shown, the ring being formed along its lower edge with an inturned flange 11, upon which the movement is adapted to rest.

Rotatably mounted in the pendant B is the radially disposed winding stem 12, the 75 axis of rotation thereof coinciding with the major axis of the elliptical body portion, and extending through an opening 13 in the swing-ring C.

The inner end of the winding stem 14 is 80 squared and is adapted to co-operate with winding mechanism not shown. As indicated in Fig. 1 the opening 13 in the swing-ring is sufficiently large to clear the end 14 of the winding stem when the ring is swung 85 around the pivot 9.

The outer diameter of the lower part of the swing-ring is somewhat smaller in diameter than the aperture 3 in the body portion thereby affording a space to receive the vertical wall 15 of the cap D. The cap D comprises a bottom 16 joined to the vertical wall 15 by an inclined wall portion 17. The lower outside portion of the ring C is chamfered to conform to the inclined wall portion 95 17 so that the cap may be slipped over the bottom of the ring C until it abuts against the shoulder 10 thereof, the flange being held positioned solely by friction between the two meeting surfaces. The cap is provided with an opening 18 adapted to register with the opening 13 in the swinging ring, the hole being also proportioned to clear the end of the winding stem 12. 100

In order to insure the proper position of 105 the cap relative to the opening 13 in the swing-ring the cap is provided with a notch 19 in the upper edge of the wall 15, said notch being adapted to embrace the lug 20 extending from the shoulder 10 of the swing-ring. 110

By tapering the lower portion of the cap

as by means of the inclined wall 17 the cap will clear the edge of the aperture 3 when it is swung about the pivot 9, as indicated in Fig. 1. Thus, the cap may at any time 5 be instantly removed from the swing-ring so as to be entirely separated from the watch case.

The chief object of providing a cap readily removable without necessitating the removal 10 of fastening means such as screws or snaps and the like is to render it possible to subject the cap to a sudden jar such as it would receive by throwing it sharply upon a table for the purpose of discharging accumulated 15 magnetism which it had previously absorbed.

It is a well known fact that the balance 20 wheels of watches frequently become magnetized to a degree rendering operation of the movement difficult. While a magnet will act through a vacuum or through glass or wood the magnetic flux seems to prefer soft iron to any other medium.

Applicant is aware that watches have been provided with soft iron cases to prevent 25 magnetic distribution in the movement, but many of these devices require special machinery for demagnetization. Applicant's device may be demagnetized by simply removing the cap and subjecting it to a jar 30 and then replacing it in its original position. A further function of the cap is to protect the movement against the accidental denting of the back of the watch case.

While applicant has shown a considerable 35 space in Fig. 1 between the back of the case and the cap it is evident that the bottom of the cap may be brought in close proximity (as shown in dotted lines in Fig. 1) to the back of the case without interfering with its anti-magnetic function. Further 40 applicant's device may be applied to any make of swing-ring watch cases, as an attachment in that it is only necessary to provide the lug 20 on the swing-ring. In order 45 to facilitate removal of the cap suitable

thumb notches 21 in the edge of the wall 15 are provided.

I claim:

1. A watch case comprising a body portion having a centrally disposed aperture, 50 a movement carrying ring hinged to said case at the edge of said aperture to swing into and out of the same and having a depending chamfered portion and a cap of highly magnetic metal or material enclosing 55 said ring and having a contracted base portion engaging the depending ring portion to be frictionally held thereon for the purpose set forth.

2. A watch casing comprising a body portion having a centrally disposed aperture, 60 a movement carrying ring constructed to fit within said aperture and hinged at its upper edge to said body portion so as to swing into and out of said aperture, a cap of highly 65 magnetic metal or material completely covering all of said ring below said aperture when said ring is within the aperture said cap being removably held upon said ring and said ring on one side being formed 70 with an opening, and a winding stem supported on said casing and extending loosely through the opening in said ring.

3. A watch casing comprising a body portion having a centrally disposed aperture, a 75 movement carrying ring hinged at its upper edge to swing into and out of said aperture, said ring having a depending annular portion extending down within the body portion, and a cap of magnetic material completely 80 covering the depending portion of the ring and normally being clamped between the ring and the wall of the aperture.

In testimony whereof I affix my signature in presence of a witness.

ALBERT L. HAMAN.

Witness:

GEORGE VOELKER.
